UNITED STATES PATENT OFFICE

2,420,659

METHOD OF PROCESSING FRUIT

Raymond L. Ewald and Henry A. Skog, Olympia, Wash., assignors to Special Equipment Company, Portland, Oreg., a corporation of Oregon

Original application October 31, 1940, Serial No. 363,596. Divided and this application December 3, 1942, Serial No. 467,681

21 Claims. (Cl. 146—222)

1

This invention relates to a method for processing fruit, and more particularly the invention relates to a method for feeding, halving, peeling and pitting peaches and other fruit, and particularly clingstone peaches. The present invention is a division of our copending application, Serial No. 363,596, entitled "Fruit treating machine," which became Patent No. 2,398,780 on April 23, 1946.

The process of the present invention is illustrated, for purposes of exemplification, by a single organized automatic machine adapted to halve whole fruits, specifically peaches, wherein the peaches are positioned therein one at a time, and wherein various steps of the process are carried out in the machine by automatic means adapted firmly to hold each peach in precise position while the stem cavity thereof is peeled, and during which whole operation the peach is severed; and thereafter the severed halves are disposed into holding means which, in association with the pitting and peeling mechanism, is adapted to peel and pit the peaches while they are held in said horizontal position; and thereafter the pitted and peeled half fruit is discharged independently of the severed peel and/or the severed pit.

Among the objects of the present invention is to provide a process for processing whole fruits whereby the whole fruits are initially positioned with their stem axes inclined angularly with respect to the horizontal, during which time certain preliminary processing operations are carried out upon the whole fruit, if desired, and thereafter the whole fruits in such maintained position are then halved, and the two halves are then each swung ninety degrees about a horizontal axis lying parallel to the plane of severance through the half fruit, whereby to position each half fruit with its cut face horizontal and with the projections of the longitudinal stem axes of the two halves intersecting at approximately an angle of ninety degrees whereby the two halves with their cut faces uppermost and lying horizontal are sufficiently spaced apart so that they can be independently acted upon by peeling and/or pitting or coring devices, if desired; to provide a process for holding and handling whole fruit whereby each whole fruit is initially positioned with its stem axis inclined angularly to the horizontal, in which position the stem end is treated to remove the peeling therefrom and thereafter the whole fruit is cut through a plane thereof which is parallel and substantially coincides with the suture plane of the fruit, if it be,

5 for instance, a peach or similar fruit, and which plane is substantially through the central portion of the fruit if the fruit be, for instance, a pear, and whereby two fruit halves are provided, and whereby said fruit halves with their cut faces maintained in juxtaposition are preferably shifted longitudinally and are thereafter swung, preferably simultaneously, ninety degree about a horizontal axis lying parallel to the plane of severance whereby to position each half fruit with its cut face horizontal and uppermost and spaced apart from each other, and with the projections of the longitudinal stem axes of the half fruits intersecting; yet another object of the invention resides in processing a whole peach which comprises the step of positioning the whole peach with its stem axis inclined downwardly at a relatively acute angle to the horizontal and in which position the peeling at the stem cavity is removed and thereafter the whole peach is halved by cutting action which passes along a plane substantially coinciding with the suture plane of the whole peach so as to provide two half peaches and thereafter such half peaches are held with their cut faces in juxtaposition and thereafter each half peach is swung approximately ninety degrees about a horizontal axis lying parallel to the plane of severance whereby to position each half peach with its cut face horizontal and with the projections of their longitudinal stem axes intersecting whereby further operations may be carried out simultaneously or in sequence upon said half peaches and with relation to the prepositioned stem axes of each half peach; to provide these and other objects of invention as will be apparent from a perusal of the following specification and accompanying drawings wherein:

Figure 50 is a diagrammatic representation of the different steps and operations performed upon the fruit from the time it is fed into the machine at the feeding station and progressively travels through the machine and is ejected at the fruit discharge station.

In order to provide a fuller exemplification of the invention it will be described in detail in connection with an automatic power driven machine for carrying out certain of the steps of the process claimed herein. It will be seen that the automatic machine comprises in general an upright main frame and an extension frame, the main turret carrying fruit holding means specifically in the form of substantial cup-like members, each adapted to hold a half peach. This main turret, as will be hereinafter set forth, is given an intermittent movement by well-known Geneva mechanism, so that the cup-like members are successively brought to a sequence of stations spaced about the main upright frame. These stations comprise, first, a half fruit receiving station, whereby severed sections of peaches, specifically half peaches, are simultaneously deposited in pairs in adjacent cups in the manner hereinafter recited, and thereafter the turret is given a step movement to convey each cup with its contained half peach to a pitting station whereby the pit is severed therefrom. Subsequently said cup with the pitted half peach therein is conveyed to a peeling station wherein the peeling from the peach is severed; next two adjacent cups with the pitted and peeled half peaches therein are moved to a station, at which the processed half peaches are discharged from the machine, leaving the peelings in these cups, next the two cups with the peelings therein are moved to a scavenging station and there the peelings are removed from the cups so that the cups are ready when subsequently again moved to the first half peach receiving station each to receive another half peach from the spreader blades.

It will be understood that the half cups of the turret are successively conveyed past three various stations in rapid, intermittent order, and that, during the dwell in the movement of the turret the various processes hereinbefore set forth are carried out on the half peach. The extension frame which projects from the half peach receiving station projects laterally from the main frame and carries track or guide mechanism for the fruit transfer jaws, and also has mounted on its outer end a second turret which will be hereinafter referred to as the whole fruit turret. This whole fruit turret is provided with a series of spaced-apart fruit holding jaws and with cooperating, whole-fruit feeding mechanism, the latter being constructed to permit an operator to place a whole peach in precise and predetermined arrangement with respect thereto; whereupon it moves to carry the whole peach and position it in fixed relation to hold the fruit feeding jaws of the turret which has been brought into registering position therewith, whereupon the whole peach is then automatically grasped by these whole fruit holding jaws and, upon an intermittent movement of this latter turret, is then car-

ried to a station where the peel at the stem cavity of the whole peach is cut away.

Next, the whole fruit turret moves intermittently to a subsequent station, where means is provided for severing the flesh of the peach and the pit in a plane parallel to its suture line, the arrangement being such that the severance is accomplished through the maximum diameter of the peach parallel to this suture line. After the peach has been severed while held in the whole-fruit feeding jaws, the turret next intermittently moves to the transfer station, which is in registry with the half-fruit receiving station of the first turret, as above described. At this instant the transfer jaws moving along the transfer track grasp the severed halves of the whole peach, and holding them in exactly the same position they were in at the moment of their severance, transport these two half peaches in a straight line movement toward the peach receiving cups; at this location means is provided for depositing each of the two severed half peaches into the cup in a manner to maintain the half peach in relation to the half fruit receiving cup in such a manner that the longitudinal axis of the pit of the half peach lies radially to a half fruit receiving turret, and the cup in which it is contained, so that the subsequent pitting and peeling operations may be exactly and precisely carried out.

First.—In the present application the whole fruit, specifically a peach, is fed into the whole fruit receiving jaws with its longitudinal pit axis inclined angularly, downwardly from a line horizontally passing through the axis of the whole fruit feeding turret and the whole fruit receiving jaws which firmly grasp and hold the peach in this position while the peach has the stem cavity peeled therefrom and also while the peach is severed or split in halves and transported to the transfer station. The peach is thereafter abducted by the transfer jaws which remove the fruit halves from the whole fruit receiving jaws and hold them in this exact position while transporting them to spreader mechanism, which is arranged to deposit the halves in the adjacent cups. By feeding the whole peaches with their stem axes inclined downwardly with respect to the horizontal, as specifically illustrated in Figures 10, 21, 29 and 30, after the whole fruit is severed along a plane passing through the suture plane of the whole fruit if it be a peach or similar fruit, or centrally through the whole fruit if it be a pear or similar fruit. The two half fruits thus formed are then held with their cut faces juxtaposed and in such position are then swung substantially ninety degrees about a horizontal axis lying parallel to the plane of severance whereby to position each half peach with its cut face horizontal, and with the projections of their longitudinal stem axes intersecting, preferably at an angle of sixty degrees, and whereby in such position each half fruit is deposited into a fruit holder, which fruit holders are spaced apart and are arranged with respect to further processing mechanism so that such further processing operations may be carried out on each half fruit with respect to and relative to the so positioned stem axis of such half fruit in an accurate, simple and expeditious manner. In the present device, in the machine illustrated, by so positioning the half fruits with their stem axes inclined to the horizontal they may be translated to a spreading step, at which point spreading means is adapted to shift each half fruit substantially ninety de-

grees about a horizontal axis lying parallel to the plane of severance, so that each half peach is then positioned with its cut face horizontal with the projections of the longitudinal stem axes of the half peaches intersecting at an angle of substantially sixty degrees, and with the intersection of said stem axes passing through the vertical axis of the turret which carries the holding means for thus holding the half fruits or half peaches.

The machine which carries out the process forming the claims of the present invention preferably takes the form of an upright, substantially square main frame comprising four corner posts or angle irons 2, 4, 6, and 8 (see Figures 1, 3, and 4), suitably braced at top and bottom by cross-braces 10 and 12. In addition, other hereinafter described cross bars serve as rigid supports for these upright members. In a general way, extending laterally from this rectangular frame projects a supplementary frame adapted to be bolted or otherwise attached thereto, as shown in Figures 1 to 4, inclusive, which supplementary frame is utilized to support the mechanism which initially receives the frame, the mechanism which severs the peeling at the stem cavity of the fruit, which severs the fruit in halves and which transports the severed halves to the pitting, peeling, fruit discharging and peel scavenging mechanism.

The main upright frame hereinbefore described is provided on a relatively low level thereof with horizontally disposed shafts 14 and 16, the latter being power driven through a clutch mechanism 17 (see Figure 3) by means of a belt 18 adapted, in turn, to be driven from any suitable motor 20. The clutch mechanism 17 is of any desirable construction capable of connecting and disconnecting the power source of the main operating shaft of the machine.

The shaft 16 carries a gear 21, driving another gear 22 on the horizontal shaft 14. This shaft 14 carries two main cams 24 and 26 fixed on opposite ends thereof. Each of these cams are double-faced so as to provide cam operating means on each side thereof. Cam face 24a comprises a cam track in which operates a herein-after described roller on a vertically reciprocable slide for raising and lowering the main toll carrying slide hereinafter described. The cam face 24b forms a roller race, in which a roller on a horizontally reciprocable slide 28 shifts in a horizontal motion transversely to the shaft 14. This slide carries on its outer end a bearing pivot 30 linked to a bearing pivot 32 on an arm 34 fixed on a vertical shaft 36. This shaft has fixed bearings in the housing frame 2 of the main upright frame of the machine. Vertical shaft 36 is oscillated by the slide 28 for operating the peeling mechanism hereinafter described.

The cam 26 of the shaft 14 has a cam face 26a forming a cam race, which operates a roller, connected to and operating a horizontally reciprocable slide 38, as shown in Figure 3. This slide 38 is also provided on its outer end with bearing 40 having a vertical pin 42, to the lower end of which is pivoted a link 44. This link 44 carries at its outer end an arm 46, the outer bearing 48 of which is pinned to a vertical oscillatable shaft 50, which is mounted in the corner post 6 of the frame opposite the vertical shaft 36. This shaft 50 has affixed to its upper end an arm herein-after referred to, which, in turn, pivotally connects at its outer end to a relatively long rod running diagonally across to a universal connection

which is, in turn, connected to a mechanism that operates a sector gear reciprocable about a horizontal axis for operating the mechanism which actuates the pitting knives, all as will be herein-after set forth.

Cam race 26b operates a vertically reciprocable slide 52 (see Figure 6), the upper end of which is provided with a rod 54 having a rack tooth portion 56 operating a pinion 58 on a horizontal shaft 60. This shaft 60 has on one end a bevel gear 62 which, in turn, operates bevel gear 64 on shaft 66 having bearings on the outside of the vertical frame member and on the same level as the main fruit cup turret hereinafter described, which turret is above the lower level of the machine at which the shafts 14 and 16 are located. The shaft 66 operates the mechanism for positioning the auxiliary fruit holding means, specifically the pad over the fruit cup, for holding the half fruit from tilting during peeling and also for oscillating the fruit discharging means, ejecting the processed half fruit from the machine. These mechanisms will be herein-after more fully set forth.

A second level of the main rectangular frame of the machine bounded by the uprights 2 to 8, inclusive, provides the location for the Geneva gears for driving the main or half fruit holding turret, and also the whole fruit turret, including the driving means therebetween, whereby the main or half fruit holder turret is driven at twice the speed as the whole fruit turret. To effect this function, the shaft 14 carries between its ends a bevel gear 110 (see Figure 3) meshing with a bevel gear 112 on a vertical shaft 114 mounted in the bearing 116 carried by a cross frame 118. This cross frame is supported at one end by suitable vertical brace connected to a cross bar 120 (see Figure 7), in turn carried by the vertical upright frame members 4 and 8. The opposite end 122 of cross frame 118 is bolted to an end support by a projection 124 from a horizontal cross bar 126 carried by the opposite vertical uprights 2 and 6 of the main frame at about the level of the cross frame 118. This cross bar 126 is preferably an integral part of the substantial triangularly shaped supplementary frame carrying the whole fruit turret.

Shaft 114 carries a bevel gear 112 and also carries above it a gear 128, which latter meshes with a second gear 130 on a bearing 132 on the cross frame 118. Gear 130 meshes with the larger gear 134 horizontally fixed on vertical shaft 136 having a bearing in cross-frame 118. Turret shaft 136 is surrounded by a bearing 138, above which is a long sleeve 139, along which is fixed a Geneva gear 140 having slots cooperating with a Geneva member 142 on shaft 114. This latter Geneva member 142 has a circular periphery on which is mounted roller 144 for cooperation with the radial slots of gear 140 aforesaid for intermittently rotating sleeve 139 and for holding it stationary between partial turns. The upright shaft 114 above the Geneva member carries a sprocket gear 146 (see Figure 7) driving a chain 148 running horizontally across the frame of the machine to a larger sprocket 150 fixed to shaft 152. This shaft is mounted upon a substantially triangular frame 153 carried by and integral with the cross bar 126. This frame 153 carries a bearing for the shaft 152, and also has a heavy extension bearing 154 for the whole fruit turret shaft 155. Both of these shafts are vertical and parallel to each other. The whole fruit turret shaft 155 extends vertically upward toward the top of

the frame. The shaft 152 has pinned thereto just above the bearing 153 a part 157 of the Geneva, this part carrying the roller 158.

In addition, the shaft 152 has pinned below the support 154 a gear wheel 159 which meshes with another gear 156, which is pinned to the bottom of the shaft 155. Just above the gear 156, cam 160 is pinned to shaft 155, and above the bearing 154 the shaft 155 carries a relatively long sleeve 161 to which is keyed the cooperative part 162 of the Geneva, whereby, through the intermediary of the Geneva 162, the sleeve 161 is intermittently rotated. Sleeve 161 carries the whole fruit feed turret.

15 *Whole fruit feed station*

Means is provided whereby an operator may feed whole peaches one at a time to the whole fruit holding mechanism carried by the whole fruit turret, and such mechanism comprises automatically shiftable means preferably including a concave receiver, into which a whole peach is placed by the operator, so that the stem axis and suture of the half fruit is precisely and definitely located with respect to this receiver, whereby, 20 upon the shiftable operation of this feeding mechanism or receiver, the whole peach is automatically conveyed to whole peach gripping means preferably in the form of spaced fingers or jaws which are adapted automatically to grip the 25 whole fruit adjacent and on substantially opposite sides of the suture plane of the whole fruit, and thereafter firmly to hold the whole fruit in the precise position in which it was placed in the first mentioned whole fruit receiving means. 30 Thereafter this whole fruit gripping means is 35 turned by the turret mechanism carrying it to a plurality of stations provided with mechanism for operating upon the peach while thus precisely held.

40 Direct positioning of the whole peach in the machine and the maintenance of control of a certain alignment with respect to the suture and stem cavity is very important for efficient results obtained from successive processing operations on 45 the peach while it is fed through the machine. It is undesirable to provide feeding mechanism which gives the operator any particular leeway in properly placing the peach in the feeding jaws of the whole fruit turret, and therefore the hereinbefore described means is provided for eliminating all chance and guesswork by the provision of means whereby the operator merely places the stem cavity of the whole peach over a locating means, and in the construction of the whole fruit 50 receiver with concaved walls, whereby the rounded body of the peach automatically alines its suture, so that subsequent operations may be exactly determined.

To this end therefore mechanism for feeding 55 a whole peach to the fruit holding mechanism of the whole fruit turret is illustrated as an arm 163 pivoted as at 164, and provided with a roller 165 which works in the cam slide of the cam 160. The outer end of the arm 163 has pivoted thereto an elongated arm 166, the upper end of which is pivoted as at 167, to a bracket 168 carried by the extension frame. This bracket, as shown in Figures 1, 10, and 11, is made adjustable, and is provided with a right angle arm 168 60 carrying on its outer end a guideway 170. The guideway 170 is disclosed more in detail in Figures 9, 10 and 13, and is arranged so that a block 171 is slidable therein, being normally and resiliently pushed to upward position by means of a 65 spring 172. The outer end of the slide carries the 70 75

whole fruit receiver or cradle 173 shown in detail in Figure 12. This receiver includes a substantially centrally located stem cavity positioning means 174, which is elongated as shown, and is designed to fit within the stem cavity of the whole peach.

In addition, on opposite sides thereof, the cradle is provided with concaved or rounded walls 175 which are substantially cup-shaped. These walls at the rear are cut away as shown at 176, so as not to interfere with the opening and closing movements of the lower whole fruit holding fingers or jaws, as shown in Figure 10. It will be noted that the angle arm 168 is arranged so that, when in position to place the half fruit between the holding jaws hereinafter referred to, the stem axis of the whole peach is angularly disposed with respect to a horizontal line passing through the center of the whole fruit receiving means. Specifically the stem axis is downwardly inclined about 30 degrees to such line. This is particularly important because, as the whole fruit is carried by the gripping means of the whole fruit turret, it must be maintained in this exact position.

The spring 172, by reason of its resiliency, permits some latitude in the positioning of the whole fruit with respect to the stationary support of the whole fruit receiving jaws, as hereinafter set forth, so as to accommodate fruits or peaches of different sizes.

Referring now to the turret proper and to the fruit holding jaws, it will be observed that the intermittently rotatable sleeve 161 carries an additional sleeve 177 and affixed thereto are a plurality of post supports 178, such supports being radially spaced around the central vertical axis of the turret. Each one of these supports 178, in turn, is provided with an upright extension upon which the whole fruit holding jaws are mounted. By reference to Figures 8 to 18, inclusive, the construction and operation of these jaws will be apparent. The lower jaw 181 is pivoted as at 180 to the upright 178. This lower jaw is formed with two integral spaced-apart jaws or fruit gripping fingers 181, which have concaved portions 182 and 183 adapted to engage the curvilinear contour of the whole peach on opposite sides of a plane passing substantially vertically through the plane of the suture, as shown in Figures 17 and 18.

In addition, this lower jaw 181 is provided at its rear end with an angularly disposed tooth projection 184, and is provided with a connection 185 with a coil spring 186 as hereinafter set forth. The upper jaw is made in two pieces, whereas the lower jaw is preferably made in a single piece. The details of construction of the upper jaw are shown in Figures 15 and 16. This upper jaw comprises a head portion 187 centrally apertured as at 188. The head is provided with a lateral lug 189 hereinafter referred to, and with an operating roller 190 on its upper portion, and a laterally extending tooth arm 191, the teeth of which mesh with the teeth of the arm of the lower clamping jaw of the whole fruit holding mechanism. In addition, the head portion 187 is provided with a laterally extending fruit clamping jaw 192 having a curvilinear fruit contacting face 193 for engaging the contour of the peach on one side of the plane of the suture. In addition, this jaw is provided with an upstanding lug 194, to which the upper ends of the spring 186 connect. The cooperative part of the upper jaw is formed with a round bearing 195, which easily fits within the opening 188 of the head 187 to per-

mit relative angular movement between the parts. This head is provided with a furcation in the form of a rearwardly extending lug 196, which is adapted to receive the lug 189 therebetween that is formed on the cooperative portion of the first portion of the upper gripping jaws. In addition, this part of the jaw is provided with a forwardly extending gripping portion 197, which is arcuately curved as at 198 to grip the contour of the peach on the opposite sides of the suture planes, as shown in Figures 17 and 18. The furcation 196 and the cooperating lug 199 provide a lost motion connection, which permits two portions of this upper jaw to have vertical adjustment, as shown in Figures 17 and 18, whereby in the event a peach is held, which is of smaller diameter on one side of the suture plane than the other, the upper gripping jaw will adjust itself accordingly, whereby to hold the peach precisely as it is inserted between these jaws when they move together under the tension of the closing springs 186. There are a pair of springs for each jaw—one on each side of the vertical plane through the central portion of these jaws—the upper springs being attached to the pins 194 and 194', respectively, and the lower ends of the springs being attached to the pins 185 and 185' of the lower jaws. It will be noted that the holding portions 181, 181' of the lower jaws and the portions 192, 197 of the upper jaws are spaced apart to permit the entry of the saw therebetween, so that the saw may completely sever the entire peach and its pit while held in these jaws. It will be further noted that this space between these fingers 181, 181' and 192 and 197 lies in the suture plane of the peach, which is approximately the plane of the maximum diameter of the peach, and parallel thereto.

Means for operating the jaw mechanism of the whole fruit holding means comprises a cam 200 which is splined to the upper end of the shaft 155. This cam is provided with an internal cam-way adapted to receive a roller 202 mounted upon a slide 204 disposed immediately beneath the cam and lying transversely across the shaft 155. The slide is suitably slotted as at 206 (see Figures 8 and 14) to permit movement of the slide back and forth transversely across the axis of the shaft 155. The slot is adapted to move in guideways 208 fixed to the extension support of the machine. The bottom portion of the slide is provided with two depending lugs forming extensions thereon. These lugs are 180 degrees apart. The cam race 202 of cam 200 extends 360 degrees of a total annular travel of the cam. When the slide 204 is moved toward the feed-in station, i. e., away from the main or half fruit turret, the depending lug nearest the main turret moves toward the feed-in station, and thereby pushes the roller 190 on the top of the upper finger of the corresponding whole fruit jaws inwardly toward the shaft 155, thereby positively to open these fruit jaws. Simultaneously, the opposite lug 210, which is spaced 180 degrees therefrom, moves in the same direction to permit the spring 186 to close the oppositely located fruit clamping jaws about or into engagement with a peach positioned by the fruit-receiving saddle 175, and thereby hold the whole fruit firmly between the fingers of the jaws. Any variations in size of successive peaches are automatically compensated for by the yielding action of the springs 186 between the upper and lower clamping jaws, and any deviations in size on opposite sides of the plane of the suture of the peach are compensated for by the relative move-

ment between the members of the upper fruit jaw.

The upright 178 on turret 177 has rigidly bolted thereto as at 212 a laterally projecting backing member 214, which is shaped as shown in Figure 8 thereby to position and firmly to hold the rear portion of the peach positioned between the clamping jaws by the whole fruit receiver 175.

By reason of the foregoing construction, the whole fruit turret is intermittently rotated to position each pair of fruit holding jaws at the receiving station, during which time the jaws are automatically held in open position while a whole peach is fed onto the peach-receiving cradle 175 in a manner hereinafter set forth, and thereafter the receiver 175 is moved upwardly to position the peach, as shown in Figure 10, during which time the upper and lower jaws of the clamping members are cam released so as to resiliently approach the peach to grasp and hold it firmly and precisely in the before described predetermined position.

At the same time that the turret is moved, the shaft 155 is synchronously driven to operate automatically the cam and slide hereinbefore mentioned to cause these proper opening and closing movements of these jaws in timed relation.

Further referring to the foregoing mechanism, once the whole peach is placed manually with its stem cavity registering with the positioning nib 174 of the fruit cradle, as illustrated in Figure 9, the whole peach will thereafter be raised upwardly to the position shown in Figure 10, with the stem axis downwardly inclined from the horizontal, as therein shown. At this time the whole fruit jaws firmly grasp the fruit as hereinbefore set forth, whereupon the fruit-receiving cradle moves downwardly, the turret then automatically shifts to the stem cavity trimming station; and at the same time an empty set of whole fruit holding jaws is brought into registration ready for the next upward movement of the whole fruit receiving cradle.

At the stem cavity peeling station means is provided for removing the peeling in the stem cavity of the whole peach. The present mechanism is designed efficiently to remove the peeling from the stem cavity of the whole peach, which is of elongated shape. Experience has shown that in the majority of peaches these stem cavities are of this shape and not round. In the present instance the stem cavity peeler is disposed to operate upon the whole peach while the latter is held in the whole fruit turret, and is the first station of the mechanism operable upon the whole peach while in the holding jaws of this first turret. The mechanism for removing the stem cavity and peeling is shown in Figures 19, 20, 21, 22, 23, 27 and 28.

Referring particularly to Figure 1, mounted on the top of the frame 12 is a motor 216, which drives a belt 218 to pulley 220 on the shaft 222 (see Figure 28). This shaft, in addition, carries a worm gear 224 driving another gear 226 (see Figure 20) on a vertical shaft 230. This shaft 230 is connected by means of a universal joint 232 to a telescopic shaft arrangement 234, which has pinned to the lower portion of the telescopic shaft arrangement a bevel gear 236. This telescopic shaft arrangement includes a driving key 238 of usual construction, and a spring 240 whereby to cause the bevel gear to be driven from the shaft 230 while permitting relative reciprocation of the movable portions of the telescopic shaft, and while at the same time permitting a swinging movement of the cutter mechanism driven by the bevel gear 236, as hereinafter set forth.

In addition to the telescopic shaft 234, there is provided a swinging frame arrangement adjacent thereto comprising a bracket 242 rigidly mounted upon a support portion 244 of the main frame. This bracket 242 includes an upstanding pin-like bearing 246, upon which a hub portion 248 of a mounting is adapted to oscillate. This hub portion 248 has a depending socket 250 having a depending shaft 252 affixed thereto as at 254. The bottom portion of this arm has slidably, adjustably affixed thereto a carriage 256 (see Figure 21). The upper portion of this carriage is provided with a smaller sleeve 258 carrying a pin 260, on which a pair of rollers 262 are mounted. The lower portion of the sleeve carries a ring-like member 264 having a depending bracket 266, which, as shown in Figure 20, comprises arms 268 and 270 and a sleeve-like support 272 for the bottom portion of the telescopic shaft 234. The central arm 270 has a lower portion 276 forming at its bottom end a bearing 278 for the bottom portion of the telescopic shaft arrangement 234. Mounted in the arms 268 and 270 of this lower carriage is a shaft 280, to which is affixed a bevel gear 282 for driving the same from a bevel gear 283. Also mounted upon this shaft 280 between the arms 268 and 270 is the peeling cutter arrangement comprising stem cavity gauge 283, preferably formed as a wheel or disk, and having oppositely disposed hubs 284 which are loosely mounted upon the shaft 280. This gauge wheel 283 is rotatably mounted so that it can roll down into and out of the stem cavity, carrying with it a pair of rotating cutter blades 288 and 299. By thus mounting the disk, sawing or cutting of the fruit is prevented. Adjacent each hub 284 are collars 285 and 286, which are keyed to the shaft 280 and form a support for the above mentioned cutter blades 288 and 299, which are of the general configurations shown in the drawings, and are attached to the collars 285 and 286 by means of the screws 292. It will be noted that the cutter members are staggered 180 degrees, so as to counterbalance the high speed rotation of the cutter shaft. Each cutter comprises generally concaved portions 294 on opposite sides of the gauge wheel as shown in Figures 24 and 20, and because of this opposite arrangement of these concaved portions of the cutters in combination with the gauge wheel 283, which is adapted to roll in the central portion of the peach cavity, the cutters as they rotate will completely and precisely cut and sever the peel from the stem cavity.

Means is provided for oscillating the cutter about its swingable bearing pin 246, and, in association therewith, there is provided a cam mechanism to give the cutter a definite swinging movement. By reference to Figures 2, 21, and 25, it will be seen that means is provided to place the stem cavity peeling cutters in position so as to rotate and cause a swinging movement resiliently inwardly toward the stem cavity of the peach, and also a positive displacement movement away from the stem cavity of the peach and/or substantially up-and-down or vertical, reciprocatory movement longitudinally of the longer axis of the stem cavity.

Referring particularly to Figures 8 and 25, 70 mounted upon the whole fruit turret shaft 155 at the top thereof is a cam 300 which is pinned to shaft as at 302. This cam is provided with a camway 304 shown also in Figure 25. Slidably mounted transversely of the shaft 155 is a slide 75 306, which is slotted as at 308 to permit such

movement of this slide. Such slide carries on its upper surface a roller 310 which operates in the cam slide 304, whereby upon rotation of the shaft 155, the slide is reciprocated in the manner shown in Figure 25. This slide at one end carries an operating arm 312 provided with a roller 314. This roller is adapted to contact a vertical plate-like member 316, which is mounted upon the pivoted member 250, which swings with the assembly. A depending arm 318 having a cam portion 319 formed on its lower end, is pivotally mounted at 320 on the rigid portion of the support 242, and it is provided with an inwardly extending shorter arm 322 adapted to be disposed between upper and lower screws 324 and 326, and by means of their adjustment are adapted to determine the position of the cam portion of the arm 318, whereby to determine the adjustment of the movement of the cutter as it approaches the peach stem cavity. Cam member 318 prevents the cutters contacting the jaws 181, if no fruit be therebetween. The foregoing roller 314, in cooperation with the plate 316, positively forces the cutter out of contact with the stem cavity so as not to interfere with the movement of the whole fruit turret and the whole fruit holding means. On the other hand, a coil spring 328 has one end attached as at 330 to a ring 332 pinned to the depending sleeve 256, and has its opposite end fixed to a pin 334 on an actuatable arm 336 in turn fixed to an oscillatable shaft 338 hereinafter referred to, whereby the spring 328 constantly tends to draw the swingable stem cavity cutter toward the peach when the slide 312 and its roller 314 swings to the left, as viewed in Figure 19.

In addition to this movement, means hereinbefore referred to is provided for raising and lowering the cutting mechanism in synchronized relation to the inward swinging movement of the cutter toward the stem cavity. This is accomplished by the mechanism in Figures 19, 21, 22, and 23. By means of this arrangement, when the rod 252 is shifted by the roller 314 on the slide 312, and by means of the spring 328, it will shift the entire frame or support 266, which carries the cutter head, while at the same time the sleeve 256 carrying the cutter head may be shifted vertically with respect to the rod 252, due to the slot and block arrangement therebetween. The means for vertically raising and lowering the sleeve 256 carrying the cutter head comprises the bar 336 hereinbefore described, which, when actuated, is adapted to raise and lower the sleeve 256 by means of contact with one of the rollers 262 thereon. The shaft 338 that actuates the bar 336, as shown in Figure 25, is provided at its opposite end with a roller 348, which is shifted by a cam 452 mounted on the shaft 136, as shown in Figure 23 of the drawings. Likewise, the rod 234 will be raised and lowered vertically with respect to the sleeve 243, and it also will be retained in vertical alignment by the abutment 238 riding in the slot formed on the sleeve 243.

If desired, the means for giving the carriage 256 a vertical, reciprocatory movement, may be omitted, and merely the swinging movement may be imparted to the carriage. It is preferred, however, to give the combination of movements. It will be appreciated that, inasmuch as the elongated stem cavities of successive peaches vary in length and depth, the gauge wheel is provided to roll down through the cavity, allowing the opposed cutters to do the peeling, regardless of the length or depth, and in con-

formity with the shape of the stem cavity. The vertical movement and the swinging or oscillatory movement are independent of one another but in timed relation.

Means for sawing or severing the peach in halves

Means is provided for sawing the flesh of the peach and the pit into halves, and particularly for sawing the same in a plane parallel with, and preferably through, the plane of the stiture of the peach. This means is constructed so that, when the sawing operation is carried out, the severed halves of the peaches will not be turned by the rotating saw prior to being positioned on the spreader wings, whereby a simple pivotal movement of the wings serves properly to position the peach halves in the half peach receiving cups. In order to insure control of the position of the half peaches during the sawing operation, the sawing station is disposed so that the saw is adapted to swing in and out at its station into contact and through the flesh and pit of the peach and while the peach is firmly held top and bottom by the peach holding jaws and by the backing member 214, whereby there is no chance for the peach to turn, during the sawing operation.

As heretofore pointed out, peaches are very often larger on one side of the suture than the other, and since the peach must be held firmly and exactly positioned and held during sawing and while being shifted to the spreader plates, means is provided, so that the upper jaws can work independently within certain limits to take care of the difference in diameter of the two halves on opposite sides of the suture plane through which the cut is made. This adjustability is not necessary on the lower jaws because the side of the peach opposite the suture always presents a uniform, rounded surface.

The sawing mechanism is illustrated in Figures 1, 2, 25, 27 and 28. Shaft 222 (see Figure 28) is provided with a pulley 352 through and with a belt 354, which drives a second pulley 356 on a shaft 358 carried by and mounted in a carriage 360, supported on a swinging arm 362 adjustably mounted as at 364 on a depending arm 366 carried on a bearing member 368 concentrically surrounding the drive shaft 322. An adjustable connection 370 is connected with the depending arm 366, and is operated by a rod 372 actuated by the slide 306, as shown in Figure 27. The mounting member 360 is provided with ball bearings 374 and carries the saw 376, which is driven at high speed by means of the rotatable shaft 358.

Transfer mechanism for the sawed halves of the peach

After the peach is sawed at the sawing station, the two halves retained in sawed position within the whole fruit holding jaws are moved by the turning of the whole fruit turret to the next station, which is the fruit transfer station. At this station means is provided for grasping the two halves of the fruit with their cut faces in confronting engagement and for transferring them from the whole fruit holding jaws to the half peach or half fruit spreading plates, which constitutes means for depositing the two halves of the peach into the half fruit receiving means, preferably in the form of cups. Reference is had to Figures 1, 2, 8, 25, and 29 to 38, inclusive,

for a proper illustration of this fruit transfer mechanism.

The main fruit holding turret

Means is provided for holding the divided peach halves or sections in a manner so that such sections supported with their cut faces exposed may be subjected to one or more operations. As shown clearly in Figure 27, the saw in its high speed rotation is adapted to be oscillated by means of the slide mechanism to cut completely through the flesh of the peach and through the pit of the peach. In this connection it will be noted that the saw will pass into the kerfs formed in the peach holding jaws, and will, likewise, pass through a central kerf formed in the backing member 214, which, when the jaws 179 are in registration with the backing member 214, the kerf in the member 214 registers with the kerf in the jaws, so that the saw will in the innermost swinging movement take the position shown in the left of Figure 27, showing that the flesh and pit of the peach are completely severed. Figure 2 shows the cups and how the half fruits may be deposited and held therein with the longer pit axis substantially coincident with the radius line of a turret that passes through the substantial center portion of the half-peach fruit holder, whereby the axis of movement not only of the pitting means but also of the peeling means will lie approximately parallel to the longer axis of the pit, whereby the pitting, peeling, and discharge of the half fruit from the half peach holding means is facilitated.

In the present instance, in order to carry out the foregoing, by referring to Figure 7, it will be noted that the sleeve 139 is disposed to turn inwardly on or about the main vertical shaft 136 and extends parallel above the Geneva disk 140. This disk 140 is affixed to the lower end of the sleeve 139. The upper end of the sleeve 139 carries a boss 378 (see Figure 1) having an upper disk 380, to which the bottommost spider of the fruit holding turret 382 is adjustably bolted, the adjustment serving to provide angular adjustment of the fruit holding turret relative to its turning sleeve, whereby to provide an adjustment for insuring that the half fruit receiving and spreading wings or plates hereinafter referred to are in the properly close-together position at the time the fruit halves come onto the wings.

As clearly shown in Figure 2, the turret 380 is provided with a spider providing a mounting for the half fruit receiving means hereinafter specifically shown as cups. There are six of these cups, each disposed with its center line located radially of the shaft 136. Directly surrounding the shaft 136 above the turret 380 is disposed a long sleeve 384 (see Figure 8). This sleeve forms a mounting for a plurality of devices. It is formed at its upper portion with a preferably integral outstanding projection 386 (see Figures 29 and 30), which faces toward the transfer jaws. Sleeve 384 provides a bearing for the inner shaft 136, and also provides a supporting bracket 390 for devices that operate the mechanism for releasing the clamps on the spreader plate for holding the half peaches thereon and hereinafter described. The upper end of the shaft 136 is provided with four cams which are keyed thereto. The cam 392 is provided with a raceway 394 which receives a roller 396 mounted on the end of a vertically reciprocating bar 398, which has pivotally connected to it a block 400. Directly above

is a second cam 402 which has a raceway 404, which receives a roller 406 connected to a vertical bar 408, which has a bearing portion 410 on the sleeve 384. This bar 408 is provided on its lower end with a rack 412 which actuates a segment gear 592. This segment gear is formed on a horizontal shaft 584 and operates the spreader plates 418 hereinafter described.

Directly above the cam 402 on the shaft 136 is 10 a cam 420 keyed to the shaft 136 and having a cam track 422, which engages a roller 424 on an arm 428, which is pivoted at 430 on a bracket 432, which is supported on the upper main frame 12 of the machine. The arm 428 has attached thereto a rod 434 connected at 436 to a lever 428. This rod 434 has at its lower end a threaded connection 438 to a block 440, which is pivoted on a pin 442, which is, in turn, threadedly connected at 444 to a cam bar 446. This cam bar 446 is provided at its lower end with a wedge-shaped end 448, which actuates a pair of rollers 450 and 451. In addition to the cams 392, 402, and 420 on the shaft 136, there is provided a cam 452, which actuates the roller 348 hereinbefore described.

Referring again to the vertical reciprocating slide 398, which carries the pivoted block 400, as shown in Figure 39, the block 400 slides between 25 furcations 454 and 456 of an arm 458 keyed on a shaft 460. The opposite end of the arm 458 30 carries an offset portion 462, on which is rigidly mounted an elongated rail 464 extending parallel to the rail shaft 460.

Referring again to projections 386, as shown 35 in Figure 25, it will be seen that it forms a support for the sleeve 461, and also forms guideways for the vertical bars 398 and 408. The bar 408 is held in position by a plate 466, which is bolted to the projection 386 by bolts 468. This projection 398 also forms a bearing for the inner end 40 of the shaft 460.

A transfer jaw carriage 470 is composed of two parallel sleeves 472 and 474 connected at their opposite ends by castings 476 and 478 (see Figures 26 and 33). Rotatably mounted on sleeves 472 and 474 by means of concentric, surrounding sleeves 480 and 482 are two depending arms 484 and 486, which are interconnected by intermeshing gear sectors 488 and 490. Projecting from the side of a sleeve 482 is a lateral lug 492 carrying a roller 496 which engages the rail 464. Slidable on the rail 464 is a shoe 498 having a pin 500 threaded into its underside and depending therefrom. A coil spring 502 surrounds this pin between the shoe and a lug 504, which is screwed into the lower part of the arm 484. An adjustable lock nut 506 is threaded into the lug 504 and provides an adjustment to vary the tension of the spring 502, thereby providing an adjustable pressure against the lower part of the arm 484. The function of the spring connection is to permit the cam mechanism 392 and the arm 458 that oscillate the rail 464, to force the rail to its downward position even if the arm 484 is pushed outwardly due to the oversize or larger half fruit engaged by the cup on the arm 484. This spring 502 also serves to maintain a proper tension upon the jaws on the arms 484 and 485 to transfer the fruit (see Figure 33).

The upper surface of cam 300 is provided with 70 a pin 510 providing a pivotal contact point for a crank arm 512, which pivotally connects as at 514 with a bar 516 pivotally connected as at 518 to the transfer jaw carriage 470. By means of this arrangement, the transfer jaw carriage is reciprocated back and forth on its guideways

460 and 461. This latter guideway 461 surrounds the shaft 338. In addition, the pivoted bar 516 has pivoted thereto as at 520 another bar 522, provided on its outer end with an elongated slot 524 adapted to receive a pin 526 on the opposite end of the carriage 470. Stop means for the bar 516 comprises a pair of rollers 528 and 530 each adjustably mounted on respective blocks 532 and 534 carried by stationary arms 536 and 538, respectively, on stationary portions of the framework of the machine. By means of nuts and slot connections 540 and 542, the positions of these stops may be varied for purposes of adjustment, as will be hereinafter more fully apparent.

The foregoing mechanism provides a lost-motion drive at the two opposite ends of the slot 524, which ends are adapted to contact the pin 526 with the carriage and move the latter oppositely—for instance, the crank 510 and the crank arm 512, when the crank is approaching in a direction whereat the transfer jaw is at the extreme right, as shown in Figures 8 and 25, will give too little added travel in this direction to the transfer carriage. This is due to the fact that the pivot pin 510 on the crank disk 300 is beginning to travel arcuately in a direction transversely to the longitudinal line of travel of the carriage. As the carriage approaches the ends of its respective line of travel in either direction, it is desirable at these points to give the transfer jaws time to open or close at the respective ends of travel of the carriage, and it is also desirable to make this additional length of travel adjustable in order properly and adjustably to position the half fruit into the cups at the innermost end of travel of the carriage; to wit, shown to the right in Figure 8; also properly to position the transfer jaws at the outermost stroke of the travel of the carriage jaws, as shown to the right in Figure 8, and relative to the face of the whole fruit holding jaws on the whole fruit turret.

When disk 300 rotates in predetermined direction, the crank arm 512 is moved, so that through its pivotal connection 514 with the bar 516 pivoted to the transfer carriage at 518, the bar 516 is swung in a predetermined angular direction. And thus, through pivot 520 on the bar connection with the slotted link 522, the outer end of the slot 524 contacts the pin 526 on the transfer jaw carriage. And, since bar 516 cannot thereafter swing additionally in this same angular direction, the crank arm 512 still continuing to move in the same direction it was moving, now drives the carriage forward in the same direction from the position where the fruit is taken from the whole fruit turret to the position as shown in Figure 26. The little further movement takes place after the carriage has reached the position as shown in Figure 26. This is accomplished through its pivotal connection 518, and also through contact of the outer end of the slot 524 with the pin 526 on the carriage.

As the carriage reaches near the end of its travel, the crank 510 and the arm 512 will impart but little added movement to the right of the carriage, due to the transverse major component of travel of the crank pin 510, as hereinbefore described. At this point, and also at the corresponding opposite position of travel of the transfer carriage, i. e., as the carriage reaches the extreme right, as shown in Figure 26, it is desirable to give the carriage an adjustable, additional travel. Therefore, at the position where the outer end of the bar 516 contacts stop 528, this

stop forms a fulcrum, about which the bar 516 may swing. The reverse end of the bar is connected at 518 to the carriage at a greater distance from the fulcrum than is the pivot pin 514, which is the point of application of the power from the crank arm 512 to the bar 516. Hence, there is produced a power multiplying connection, as above described, which gives the transfer carriage 470 the added length of travel. At the end of 10 this crank movement, the crank 300, as it continues, now carries crank pin 510 to the right to reverse the direction of travel of the carriage. As this occurs, the slot 524 moves relatively to the pin 526 until the lost motion has been taken up, at which time the carriage is pulled to the right by its connections, i. e., the pivot pin 514 and the opposite end of the slot 524 and the pin 526, and thereafter the same added travel is imparted to the carriage in the direction by the opposite 15 stop 530 and the outer side of bar 516.

Transfer jaws

As the whole fruit turret jaws 179 come to rest in registration with the horizontally shiftable flat dividing plate 546 (see Figure 8), which plate is 20 horizontally movable along and beneath the two round carriage guides 460 and 461, as hereinafter referred to, these transfer jaws are in closed position about the confronting severed halves of the whole peach. The shiftable partition plate 546 at this time is faced about one or two inches from the periphery of the peach halves held by the jaws 179. The whole fruit jaws are brought to this position as the transfer jaws are moving to the right (see Figure 8) in abducting the prior two halves to the spreader plates, for subsequent deposition into the fruit holding cups of the half fruit turret. The halves of fruit are deposited in a manner hereinafter recited, and the jaws are 25 swung apart to open position, as hereinbefore set forth; and then the transfer jaw carriage starts its return movement to the left (see Figure 8), or toward the whole fruit turret. As these transfer jaws come opposite to the two half peaches held in the whole fruit turret jaws 179, the transfer jaws are swung inwardly resiliently by the shiftable track mechanism, hereinbefore set forth (see Figure 23). Being thus moved, the two opposite transfer jaws grasp the opposite halves of 30 the peach. Thereafter, these jaws are again moved to the right (see Figure 8) toward the main turret. Before the start of this last mentioned travel, the whole fruit jaws 179 open, and the whole fruit turret moves counterclockwise one 35 station. There are six such pairs of whole fruit jaws.

As shown clearly in Figure 33, the transfer jaws comprise substantially semi-spherical shells 550 attached to the downwardly depending arms 484 and 486. These semi-spherical shells 550 are constructed so as to provide clearance for the turret jaws 179, so that the jaws 179 will hold onto the half fruit while the transfer jaws 550 are moved into position to contact the half fruit. The jaws 45 550 are provided on their lower and upper edges with notches 552 and 554. These transfer jaws are cut away at the bottom as at 552 to allow the jaws 179 to reach up and contact the fruit. As the transfer jaws approach the whole fruit holding jaws 179 at the extreme end of the transfer jaw carriage travel, the upper and lower cut-outs on the jaws register with the upper and lower fingers while the skirt of the upper transfer jaws 50 engage the surface of the peach held in the upper and lower jaws.

The fruit stop 214 on the whole fruit jaws has two purposes—one to assist in holding the rear end portion of the whole peach during the sawing operation, and, second, it also acts as a stop or gauge correctly to position the peach in the whole fruit turret jaws. This stop is cut out in front to permit the edge of the saw to enter the same to make the full cut, as hereinbefore set forth, and is also concaved on each side as at 215 to permit the transfer jaws to close onto the half fruit after sawing and while held in the upper and lower fingers of the whole fruit turret.

Longitudinally shiftable dividing blade

Means is provided during the transfer of the peach halves from the whole fruit turret to the spreading plates, hereinafter referred to, first, to fill in the gap between these plates and the whole fruit turret; and, secondly, also to cause the dividing plate to enter the severance made by the saw and while the two halves are still held by the jaws of the whole fruit turret, whereby slightly to spread the peach halves apart to ensure that each half passes onto a separate surface of the spreaders.

To accomplish these ends, it is necessary to move this dividing blade into position between the upper and lower fingers of the whole fruit turret, and therefore the mechanism for accomplishing this and the mechanism of the dividing plate will not be described.

Referring to Figure 8, it will be seen that a bracket 560 attached to a stationary part of the machine supports a horizontal guidebar 562. Slidably mounted in the bar 562 is a slide 564. Secured to this slide is a downwardly depending lug 566 which carries the separator blade 546. A spring 568 creates the urge to hold the slide 564 against a stop 570. This normally tends to place the separator blade 546 in position just in front of the spreader wings hereinafter described. Now, as the transfer carriage 470 moves outwardly to pick up the next peach, a plate 582 (see Figure 8) which is fastened to the cross member 478 of the transfer carriage, strikes against the lug 566. This causes the slide 564 to move along the slide bar 562. This, in turn, causes the separator blade 546 to enter the fruit between the two fruit halves, as shown by the position in dotted lines.

Now, as the transfer carriage carries the peach into the machine or toward the right in Figure 8, the spring 568 pulls the slide 564 along with the peach until the slide is stopped against the stop 570. From here, the peach halves slide onto the spreader blades into position for being placed into the peeling cups.

The boss or projection 582 on the transfer carriage is on that part of the slide nearest the whole fruit turret, so that the transfer carriage 470 has a movement toward the whole fruit turret independently of the slide until the depending projection 582 on the carriage abuts the boss 584 of the dividing slide, and then moves the slide with the carriage toward the whole fruit turret. A spring 568 normally pulls the slide back toward the main turret, i. e., to its position in front of the spreader wings. When the carriage retreats toward the main turret, the spring pulls the slide back toward the spreader wings. The stop 570 on the track limits the movement of the dividing blade to a position just clearing the wings.

Fruit spreader blades 574 and 576 are supported on upstanding vertical castings 578 and 580 (see

Figures 8 and 30) and are connected to these castings by tapered head screws 582. The lower end of the casting 578 is keyed to a horizontal shaft. Castings 578 and 580 have keyed to their lower portions short shafts 584 and 486, which are mounted in a bearing block 588 (see Figure 33), and the shaft 584 has formed on its opposite end segment gears 590 and 592 (see Figure 39). The gear 592 is adapted to mesh with the hereinbefore mentioned rack bar 412 and the gear 590 is adapted to mesh with a complementary rack bar, which is united to the first mentioned rack bar 412 by means of an intermediate block 596 and a long bolt 598 (see Figure 39), whereby, upon reciprocation of the rack bar 412, the rack bar 594 is likewise operable, whereby to oscillate the shafts 584 and 486 to operate the spreading mechanism shown in Figure 33. It is to be understood that these spreading plates are to be maintained in a vertical position in full lines in Figure 33 to the horizontal dotted line position shown in such figure, and whereby to overlie the half fruit cups, into each of which a half peach is adapted to be deposited. Each spreader plate is provided with an outer face, which when in vertical position, is adapted to receive a half peach thereon. By oscillating the two spreader arms to the position shown in full lines in Figure 33, with their rear faces confronting, two peach halves carried by the transfer jaws, may be transported onto the outer faces of these spreader plates.

Means is provided to hold each peach half temporarily on each spreader plate during the time that each spreader plate is shifted from the vertical position down to approximately horizontal position; and also means is provided for releasing the fruit clamping means from each spreader plate, whereby to release the half peach therefrom for deposition into the underneath cup. Also each spreader plate is provided with means to prevent adhesion of the relatively sticky cut face of the half fruit to the spreader plate.

The means for holding each half peach on each spreader plate, comprises a lower bar 600 having its front edge arcuately disposed and connected to each one of the spreader plates 574 and 576 by screws 602. This allows the half fruit to be moved onto the supporting bar 600, as shown in Figure 30. The upper portions of the spreader plates 574 and 576 have attached thereto short shafts 604 and 606 surrounded by collars 608 and 609, which, in turn, form a connection for the ends 610 and 611 of a torsion spring 612. The other end of the torsion spring is fastened to a collar, which, in turn, is pinned to the shaft 606. Collars 608 and 609, which are loosely mounted on the short shafts 604 and 606, form a bearing support for arms 616 and 618. These arms 616 and 618 form the upper holding means for each half fruit after they have been deposited upon the spreader plates 574 and 576, and have their lower surfaces beveled off as at 620 to prevent the half fruit from being released from the spreader plates before the upper holding arms 616 and 618 are raised to allow the release of the half fruit. Each spreader plate has a tapered entering edge 622 to allow the half fruit to be easily moved across the front surface. Three elongated, cutaway portions 624 are formed on the outside surface of each spreader plate to provide a means whereby the inner cut face of the half fruit will be prevented from sticking to the spreader plates 574 and 576 (see Figures 30 and 33).

Referring to Figures 29 and 30, to the upper peach clamping fingers 616 and 618, they have provided at their opposite ends lugs 628 which cooperate with releasing means hereinafter described. In addition, lugs 628 are formed on the upper surface of the holding arms 614 and 618, which cooperate with the depending lug 630, which projects downwardly below the surface of the slide bar 562 and is formed integral with the short bar 632, as shown in Figures 33 and 35. Formed on the opposite side in the end of the bar 632 is a roller 634 which is attached to the bar 632 by means of a bolt 636, threaded into the bar. As shown in Figure 29, the rail 562 has formed on its righthand end a horizontal slot 638 and in another slot 640 which is formed on an angle. Each slot is adapted to receive a bolt 642 which has its opposite end threaded into the short bar 632 as shown in Figure 33.

Referring again to transfer carriage 470, it has attached to its under-surface, as shown in Figures 29 and 33, a bracket 644 formed on its lower surface with a shoe 646, which has its forward end tapered upwardly as at 648, and its rear or lefthand end cut away at an angle as at 650. This shoe 644 engages the roller 634, which is attached to the bar 632 and at certain predetermined times raises and lowers this bar 632 to raise and lower the finger 630 that actuates the half fruit holding arms 618 and 616.

Referring to Figures 29 and 30, it will be seen that, as the fruit transferring carriage 470 moves from the feeding turret on the left to the spreader plate 622, the bracket 644, which is attached to the upper part of the arm 484, as shown in Figure 33, will engage the roller 634, thereby depressing the bar 632, which will allow the bolt 642 to be moved downwardly at an angle in the slot 640, thereby actuating the finger 630 to contact the lug 628, which will, in turn, rotate the holding finger 616 and raise it to allow the half fruit to pass onto the spreader plate. Continued movement of the transfer carriage 470 will allow the shoe 646, formed on the bracket 644, to pass over the roller, as shown in Figure 30, which at that time allows the torsion spring 612 (see Figure 40) to exert a rotative force on the sleeve 608, which will permit the upper holding finger 616 to be released and clamp the fruit between the lower platform 600 and the beveled undersurface 620 of the upper holding arms 616 and 618. Upon the return movement of the transfer carriage 470, the arms 484 and 486 are open or spread, and the shoe 644 is out of the path of the roller 634, which allows the carriage to return to the left.

Referring now to Figure 8 in describing the operation of the dividing blade 546, the associated spreader plates 622, the peach clamping mechanism associated with the spreader plate, and the cooperative fruit jaws 179: when the divider plate has moved to the position shown in the dot-and-dash lines, which is its outermost position, that is to say, nearest the whole fruit turret, the plate lies about as shown in such dot-and-dash lines, so that approximately a little more than one-half of each peach half overlies this divider plate as the peach is held by the clamping jaws on the whole fruit turret. At this time the transfer jaws also overlie the peach halves and are about to move inwardly to embrace the peach halves. The release of the peach halves by the fruit jaws 179 and the embrace of the peach halves by the transfer jaws is almost simultaneous. In this position the dividing plate has entered the

kerf or line of severance in the peach halves, which has heretofore been made by the sawing mechanism. From this position just described, the transfer jaws and dividing plate now move together to the right, as viewed in Figure 8, in a direction toward the main turret which carries the half fruit cups. The peach halves are carried between the dividing plate and the transfer jaws, the dividing plate lying between the peach halves and thus the peach halves are thus moved toward the spreader plates or wings. The dividing plate is brought to rest by the stop 570 in vertical registration with the vertically positioned spreader wings and almost in contact therewith. There is a slight clearance between the dividing plate and the forward edge of the wings so as to permit the wings to oscillate from such vertical position to horizontal position. At this time the wings are vertical and, since the dividing plate thus comes to rest, the transfer jaws continue to move to the right, as viewed in Figure 8, independently of the dividing plate to a position such that the transfer jaws are opposite to and laterally overlie the spreader plates, as shown in full lines in Figure 8. As these transfer jaws near the end of their stroke, the pivoted fruit gripping or clamping finger 616 on the upper edge of each spreader wing is automatically caused to drop by spring means 612 and the upper end of each finger (there is a finger for each spreading plate) enters the upper notch of its respective transfer jaw to engage the upper edge of the peach half and hold it against the lower and horizontal ledge 600 on the base of each of the wings. This ledge 600 preferably extends at right angles to the outer wall or face of the spreader plate. The fruit clamping or gripping bar 616 is provided with an inwardly inclined face so as to exert a pressure inwardly against the rounded face of the peach, whereby to hold the half fruit on the wing. In short, the inner component of the wedge-shaped portion of each clamping bar 616 acts inwardly and downwardly against the vertical face of the wing and the ledge 600, whereby to hold the half peach firmly yet resiliently in vertical position thereagainst.

When the transfer jaws have moved to the position shown in full lines in Figure 8, they next move laterally outwardly, as shown in dotted lines in Figure 33. Subsequently they move with the carriage in a reverse direction toward the whole fruit turret. However, this reverse movement does not start until the jaws have moved outwardly to clear the fruit on the wings. After the wing clearing movement of the transfer jaws has occurred, the wings are now actuated as hereinbefore described, to carry out a shifting from vertical position shown in full lines in Figure 33 to the dotted line position shown thereat.

In the down position, they are directly over the fruit cups which at this time, due to the timed intermittent movement of the half fruit turret, have been brought into registration with and directly underlying the place where the half peaches are to be deposited by these wings. As the wings just about reach the horizontal or downward position, the dividing plate or blade 546 begins its travel toward the whole fruit turret. The carriage 470 with the transfer jaws thereon has already started its motion toward the whole fruit turret, and just about as the transfer jaws begin to get into proximity with the whole fruit jaws, which in the present case means a movement of the carriage about four and ⁷⁵ five-eighth inches, the dividing plate then also

starts to move with the carriage toward the whole fruit turret. Thereafter the transfer jaws and dividing plate move together up to a position relative to the whole fruit holding jaws, as shown in the dot-and-dash line of Figure 8. The dividing plate travels in this direction two and one-eighth inches.

While this is taking place, the spreader wings, being in down position, the fruit clamping members 616 and 618 are automatically released by a slide, which is located under the bearing for the wings. This mechanism is shown particularly in Figures 33, 36, 39, 40 and 41, wherein is disclosed the wedge 446 which is adapted to be projected between the two rollers 450 and 451, whereby to actuate reversal of the opposed slides 652 and 654. Each one of these slides is adapted to release a gripping finger, and the wedge is adapted to be reciprocated vertically downwardly between the rollers, there being one roller on each slide, and the two slides are arranged to be moved outwardly in opposite directions. The two rollers are interconnected with the slides in the manner shown in Figures 33 to 41, so that as the wedge descends the rollers are forced apart against the tension of the spring 656, and thus these two oppositely connected slides are brought toward each other. Each of the slides 652 and 654 are supported in the block 588, which is, in turn, supported by the lugs 390 formed on the sleeve 384 hereinbefore described. There is attached to the outer ends of each of these slides 652 and 654 brackets 658 and 660, which have formed on their outer ends lugs 668 and 670. These lugs 668 and 670 contact the projecting fingers 626 formed on the opposite end of the holding bar 616. When the wedge-shaped end of the vertical bar 446 is pressed downwardly to separate the rollers 450 and 451, they, in turn, being attached to the slide bars 652 and 654 will move the bars toward one and another, as shown in Figure 37, which will contact the projection on the rear portion of the finger 616, which will then rotate the finger 616 about the shaft 606 to release the half fruit from the spreader wings, and allow it to drop into the fruit cup, as shown in Figure 33. When the wedge-shaped bar 446 again raises, the two rollers 450 and 451 will move together and allow the spring 656 to return the slide bars 652 and 654 to their original starting position. It will thus be seen that these slides 658 and 660, by reason of their radial vertical extensions, the latter will contact the outer end of the fruit gripper and hold the fruit gripper open for a substantial arcuately upward movement of the wings until the wings are lifted sufficiently, so that they will not pick up the peach again after once depositing the peach in the cup. The wings thereafter continue to rise to vertical and juxtaposed position, and the cycle of movement of the wings is thereafter repeated. The wedge-shaped bar 446 is provided with a coil spring 672, which holds the weight of the wedge 446 off of the rollers when the wedge is not forced down by the cam 420.

The underside of the carriage is provided only on one side with the horizontally extending actuator or bracket 644 extending toward the main turret, which bracket moves with the carriage horizontally at one side of the track and at one side of the dividing plate. This actuator engages the oscillatable slide 632 (Figures 33 and 35) mounted on a part of the track 562 adjacent the center post of the main turret. This slide 632 has two spaced studs 642, which enter slots in the stationary track. One slot which is nearest the

center post of the main turret, is horizontal, and the other slot is inclined, and two studs 642 enter these respective slots. Now as the bracket 644 moves with the carriage 470 toward the main turret it contacts the roller 634 on the slide 632 and moves the slide to the right, as shown in Figure 29, whereby to cause the lug 630 of the slide to contact arm 628 on the first finger and raise this finger onto the spreader plate. The horizontally extending bracket 644 on the underside of the carriage 470 is disposed to override the roller 636 on the slide until just before the carriage 470 reaches its innermost position opposite the spreader wings. At this time the bracket 644 is cut away so that the roller is released and the fruit holding clamp 616 drops down to hold the half peach on the spreader plate. This latter is a spring actuated movement so that the half peach is resiliently held on the spreader wing. This spring is on the pivotal post of the fruit finger 616 and is a torsion spring that normally throws the finger to down position. The two springs are oppositely wound on opposite sides of the machine.

25 A spring 568 (see Figure 8) interconnected with the slide 632 and the dividing blade slide 564 normally tends to pull the blade 546 toward the main turret against stop 510 and further so that, when the bracket 644 on the carriage drops off the roller on the slide after depressing the slide, this spring tends to again raise the slide for the next operation.

Peach pitting

35 As shown somewhat briefly in Figure 2 of the drawings, with reference to the pitting station as shown by the numeral 876, it will be noted that the pitting blades are shown as positioned to move with respect to a line passing radially through the turret axis 136 and substantially centrally of the cup carrying the half fruit. The details of construction and the specific form of the pitting mechanism are not shown here since the specific pitting construction is identical with the pitting operation shown in the prior application of Raymond L. Ewald and Henry A. Skog, Serial No. 185,332, filed January 18, 1938, entitled "Fruit treating apparatus," now issued as Patent No. 2,280,813, of April 28, 1942, reference to which and to its divisional application, Serial No. 430,840, filed February 14, 1942, wherein the pitting mechanism is claimed, is made for the specific pitting apparatus and to the manner in which it operates upon the half fruit, and specifically with relation to the arrangement of the stem axis of the half fruit as it lies in the cup 732 at this pitting station. It is sufficient to state that in this form of pitter two curved pitting blades are utilized, which sever the pit section from the half fruit, and no claim is made to this pitting mechanism per se, except insofar as it may cooperate and combine with the steps of the process hereinafter claimed. It will be noted that the pitting blades arcuately move about an axis which is parallel to and closely adjacent the longitudinal stem axis of the half pit, disposed relatively close to the cut face of the half fruit when positioned in its cup.

70 In Figure 2 of the drawing, the opposed pitting blades are shown associated with one of the cups, and, as heretofore stated, are preferably of the construction shown in the prior Ewald and Skog patent aforesaid. These blades are arranged to cut around the under surface of the half pit during the pitting operation to an overlapping po-

sition, at which time, when the pitter head rises, the blades are lifted to carry the severed pit away from the pitted half peach, so that, when these blades are again opened, the pit will be kicked out or ejected away from the pitted half peach. The cup in the meantime will have moved to the next station, which is the peeling station, leaving therein the pitted half peach with the pit removed therefrom.

The peeling mechanism

The peeling mechanism is at the next subsequent station, and no claims are made to the specific peeling mechanism herein, except insofar as the movement of the peeling blade is concerned with relation to its arcuate movement about the prepositioned stem axis of each half fruit as it lies in the cup at this station, and except insofar as such movement relates to the remaining process steps which accomplish the exact positioning of the stem axis of the half fruit in the cup so as to cooperate with the movement of the peeling mechanism and/or the pitting mechanism. The peeling mechanism is disclosed in the parent application, Serial No. 363,596 and is claimed in another divisional application, Serial No. 293,253, filed September 2, 1939, reference to both of which is herewith made for the disclosure of said peeling mechanism and its co-operative relation with the prepositioning of the half fruits thereto. Referring to Figures 3, 5, 42 and 43, wherein means are shown for operating the pitting and peeling mechanisms, and also means for driving the two vertical shafts 36 and 50, as hereinbefore described, the shaft 36 is provided on its upper end with a loosely mounted collar 700. This collar has formed thereon a pair of extending arms 702 and 704. By means of a pin and slot connection 706, the arm 702 is affixed to the flexible connection 708, which, in turn, is connected to a bar 710, which has at its opposite end a smaller flexible connection 712 with a slotted arm 714 (see Figures 1 and 42). This arm 714 is pivotally supported as at 716 on a vertical reciprocating frame or head 718 that supports the pitting and peeling mechanism. Frame 718 is reciprocated vertically by means of the cam 24, hereinbefore described. A vertical slide 720 is provided with a roller 722 which engages a cam track 24a formed on the outer surface of disk 24. The rotation of the shaft 14 rotates the disk 24, which, in turn, has a cam track 24a thereon, which will raise and lower the vertical slide 720 by means of the roller 722, thereby causing the frame or head 718 to raise and lower in synchronous movement with the rotating half-fruit turret. As seen in Figure 5, the vertical slide 720 is connected to the frame 718 by means of an adjustable set screw 726. The frame 718 has vertical guideways 728 which are bolted to the main frame columns 2 and 4 of the machine. Upon the upper portion of the frame 718, there is provided a platform or ledge 730 to accommodate the pitting mechanism 732 and the peeling mechanism 734, the pitting mechanism being attached to the frame 718 by means of bolts 736 and the peeling mechanism being attached to the frame by means of bolts 738.

As shown in Figure 42, the driving means for the pitting device are actuated by the hereinbefore described slotted arm 714, which, in turn, is keyed to a short shaft 740. Shaft 740 has keyed on its opposite end a segment gear 742,

which actuates a vertical rack bar 744, which operates the pitting mechanism.

Means for actuating the arms 704 and 702 consists of a link connection 744, connected to the outer end of the arm 704, and its opposite end is connected to a crank arm 746 by means of the pin connection 748. The crank arm 746 is keyed to the vertical shaft 50, which is actuated by the connecting links 44 and 46, et cetera, 10 hereinbefore described. Upon actuation of the vertical shaft 50, the crank 746 imparts motion to the bar 744 to oscillate the arms 704 and 702 to actuate the drive for the pitting mechanism. Situated on the shaft 36 and directly below the collar 700 is a similar collar 750 having a crank 752, which has a flexible connection with an adjustable bar 754, and which has on its opposite end a pivoted connection 756 with a collar 758. This collar is part of an arm 760 shown in Figure 15. The arm 760 bends downwardly and is formed integral with a collar 762, which is, in turn, keyed to the shaft 764 by a pin 766. The collar 762 has also formed thereon a gear sector 768, which rotates a pinion 770, keyed on a short shaft 772. The shaft 764 which is pinned on the collar 762 has pinned on its opposite end another collar 774, which has formed thereon a gear sector 776 similar to the gear sector 768. The gear sector 776 rotates the pinion 778 in the same direction and at the same speed as the pinion 770 on the opposite side of the peeling mechanism. The shaft 764 is mounted on bearings 780 which are formed on a peeling head 782. This peeling head, likewise, at its bottom carries opposed, spaced-apart bearings 784 and 786 for the shafts 772 and 777. Each of these shafts at its inner ends is provided with a block 788 and 790, to which the opposite ends of the peeling knife 792 are affixed by means of triangular blocks 794 and 796. The peeling knife 792 is constructed in accordance with prior patents of Mark Ewald, such as Patents Nos. 2,015,666 and 1,987,611.

The peeling head 782 is provided with an up-standing bracket 798 bolted thereto as at 800, which bracket at its upper ends is provided with a laterally extending arm 802 and a guideway 804 (see Figure 47) adapted slidably to receive an arm 806 hereinafter referred to. In addition, the head is provided with a centrally apertured boss 808 adapted to receive a vertical sleeve 810 having a central enlarged opening 812, which joins with a smaller center bore 814 of the sleeve 810. The bottommost portion of this sleeve is provided with a rigid foot or pad 816, the details of which are shown in perspective in Figure 49. This pad 816 is provided with a portion 818 of larger diameter and a portion 820 of smaller diameter, there being two shoulders 822 and 824 therebetween. The top of the sleeve 810 extends outwardly through the opening in the arm 806, and a spring 826 is confined between the arm 806 and a cylindrical block 828 at its top abuts a screw 830 therat through the lateral arm 802 of the bracket 798 on the vertically shiftable peeling head. A lock nut 832 holds the nut in adjusted position to regulate tension of the spring 826, which spring, in turn, is adapted to maintain the peeling pad 818 resiliently in downwardly projecting position relative to the peeling head 782. In addition, there is provided a knock-out pad comprising a preferably circular smaller pad 834 mounted on the lower end of a rod 836 having a spring abutment member 838 pinned thereto. The upper end of this rod passes through a bore

814 of the upper end of the sleeve **810**, and is provided with a cross pin **840** acting as a stop.

In addition, a spring **842** is seated within the large bore **812** (see Figure 45) of the sleeve **810** surrounding this stem, and is confined therein between the inner wall of the upper surface of the bore and the stop collar **838**, by which means the spring **842**, which is weaker than the spring **826**, normally maintains the knock-out pad in a position lower than the surface of the pad member **818**, whereby, as the peeling head descends, the knock-out pad will first contact the pit zone of the peach, and, if the pit be present, the pad will be pushed upwardly by such contact until it seats in a countersunk recess **844** in the bottom face of the circular pad **818**. Thereafter, if the half peach in the cup be too large in size, the main pad **818**, together with the knock-out pad, will be forced upwardly against the tension of the stronger spring **826**, whereby adjustably to accommodate this larger sized half fruit. At the same time the pad pressing downwardly on the central portion of the half fruit will maintain the half fruit from turning. The knock-out pad prevents the main pad from sticking to the face of the half peach.

Cooperating with this resiliently shiftable pad **818** is a pad **846**, which as shown in Figure 49 is likewise semi-circular in shape. It has a centrally disposed semi-circular cut-out **848** which corresponds to and matches the semi-circular portion **820** of the pad **818** so as to nest therewith. In addition, this pad has two upstanding posts **850** and **852**, which are joined by circular extension **854** having an upstanding lug suitably apertured as at **856**, whereby this pad is bolted as at **860** to a depending bracket portion **862** of the peeling head **782**. A slotted portion of the bracket **862** permits adjustment of this stationary pad portion relative to the peeling head **782**. It will thus be seen that this pad portion **846** is rigidly carried by and reciprocates with the main peeling head **782**, which carries the oscillatable peeling knife **792**, so that, when the peeling head descends to bring the knife into proper position relative to the cut face of the half fruit, as shown in Figures 45 and 46, this pad **846** will be brought downwardly into contact with that portion of the cut face of the half fruit, from which the knife blade **792** emerges during the peeling stroke or cut, whereby two functions are accomplished—first, the half fruit will be held from upward tilting movement at this point, due to the inward and downward arcuate thrust of the cutting knife as it enters the half fruit; and, secondly, the outer circular edge of the pad **846** is arranged so that it contacts the cut face of the half fruit, approximately at the peel zone of the half fruit, whereby this circular edge of the pad **846** cooperates with the cutting edge of the peeling knife to form, with the peeling knife, a cooperative shearing edge. Thus this stationary edge of the pad **846** provides means for preventing the edge of the half fruit at the cut face from breaking off as the peeling knife emerges from the cut face of the half fruit upon the completion of the peeling cut in this direction.

By thus providing this stationary peeling pad **846** in combination with a resiliently shiftable peeling pad **818**, and by arranging the stationary pad **846** at the knife emerging face of the cut fruit while providing the resiliently mounted peeling pad **818** at the entrance face of the half fruit with respect to the peeling knife, the necessity of positively locking the peeling pad in down-

ward position on the cut face of the half fruit for a whole or even a part of the peeling cut, is eliminated; while at the same time during the initial portion of the downward movement of the peeling cut through the half fruit, the peeling pad **816** which is provided with adjustable resilient action in upward and downward direction, holds the half fruit firmly against the inner wall of the peeling cup. In this pad arrangement, the pad **816** is maintained a standard size for all sizes of fruit, whereas the pad **850** is replaceable with pads of smaller or larger sizes, so that the arcuate edge **846** of this pad will always lie relatively close to the path of movement of the peeling knife, depending upon the size of the half fruit being operated upon, whereby this edge of the stationary pad acts as a sort of shearing knife to cooperate with the edge of the peeling blade.

The half fruit receiving cups are constructed in the same manner as in the prior application of Raymond L. Ewald and Henry A. Skog, now issued as Patent No. 2,280,813, of April 28, 1942, except that the means for moving the enlarged half section into eccentric relation to the stationary half section has been slightly altered, and as is shown in Figure 44 of the parent application, Serial No. 363,596, reference to which application for a fuller disclosure of the cup mechanism and its operation is herewith made. In this connection it will be noted that the turret **580** has mounted thereon six half peach receiving cups, which are of the general conformation shown in Figures 45 and 46. One of the quarter sections **880** of each of these cups is rigidly bolted by means of a bolt **381** to the spider of the turret **382**. The other cup section **878** is hingedly mounted to the stationary section as by means of the pin **879**, whereby these two complementary quarter cup sections will make a substantial half sectional cup. These relatively swingable cup sections have a so-called closed position, wherein the two sections are eccentric one to the other, which is shown in Figure 48; and this eccentric position is accomplished by moving the swingable fruit holder toward the stationary fruit holder, whereby to press the curved wall **882** of the half fruit against the inner wall of the adjacent stationary section **880**, so that on the down stroke of the cutting blade **792**, the firm contact of the periphery of the half fruit against the wall of the cup section **880** is assured, and whereby correct peeling is likewise assured; and, subsequently in timed relation with the arcuate movement of the peeling knife **792** and about the time that is necessary to reach the bottommost part of its stroke, the actuating mechanism for the shiftable half cup is released, so that the shiftable half cup **878** is free to swing to an open position, preferably by the action of gravity. In this position the cup sections **880** and **878** will be truly concentric. At this time, movement of the peeling knife **792**, as described in Ewald Patent 2,255,04 of September 9, 1941, will push over the half fruit section **878** now in its truly concentric position and simultaneously, as the knife continues to move, it will start its upward, arcuate curve slightly under the peel, whereby continuously form the peeling cut. This whole portion of the cut will be the emerging peeling cut. The mechanism for carrying out this operation, as shown more clearly in Figures 44 and 45, consists of cam **884** which is keyed to the shaft **14** and a cam roller **886** which is fixed to a vertical slide b

886, and engages the cam 886, as shown. The slide bar 888 is guided in a guideway 890, which is bolted to the frame 4 as at 892 and 893, and this bar 888 has pivoted on its upper end as at 894 a cam finger 896 which is held in the position shown in Figure 44 by a spring 898 and a stop screw 900. Upon raising the bar 888, the cam finger 896 contacts a roller 902 on a depending arm 904 pivoted on the shaft 879 and having its upper portion formed integral with the right-hand movable section of the fruit cup 878.

Due to the tension of the spring 898, the cam finger 896 exerts a pressure on the roller 902, which, in turn, moves the right-hand portion 878 of the fruit cup toward the left-hand portion 880, thereby clamping or exerting a pressure on the side of the fruit to hold it substantially rigid in the fruit cup while the peeling is taking place. In addition, an adjustable stop screw 906 contacts an extension 908 formed on the support arm 904, and prevents the cup section 878 from being swung out of concentric alinement with the lefthand cup section 880. This type of construction for shifting the swingable cup section 878 toward the stationary cup section 880 is more positive, is also independent of the movement of the peeling knife and permits the closing of the cup section 878 before the peeling pad comes in contact with the face of the fruit, which is not possible in the prior construction because the cup thereof does not start to move until the peeling knife starts to turn. A more positive action is required in the peach machine due to the nature of the peel surface of the half peach, as distinguished from the more smooth surface of a pear. Therefore, a stronger closing action of the cup 878 is required, and this is accomplished by the mechanism shown in Figure 44.

It is thus apparent that the present invention comprehends a method wherein a whole fruit, specifically a whole peach, while held in predetermined position, and specifically with its suture plane disposed vertically, is thereafter cut into halves along a plane parallel and closely adjacent the suture plane so held, and thereafter the fruit halves are swung ninety degrees and bodily shifted to a predetermined position, such that their cut faces lie substantially in a common plane and the projections of their longitudinal stem axes intersect at an angle of sixty degrees. It is while the two half fruits are in this latter position, with their stem axes so positioned, that they are both pitted and peeled, by forming cuts through the flesh of the half fruits arcuately about centers lying substantially on such longitudinal stem axes. In case of the pitting cut, the cuts are preferably provided by forming two simultaneous cuts beginning at the cut face of the half fruit and proceeding downwardly through the flesh arcuately around the half peach section, the line of cut being formed with the longitudinal stem axes as a center, such stem axes lying especially at the cut face of the half fruit, and the peeling cut being made by a single arcuate cut beginning at the cut face of the half fruit and following arcuately therethrough beneath the peel and terminating at the cut face of the half fruit, the arcuate line of cut being formed with the longitudinal stem axis as a center.

It will be noted that in the mechanism for carrying out this method, the two half fruits simultaneously are deposited into the cups and shifted by the second turret so that the first cup with its contained half fruit is presented to the

pitting station, at which station the half fruit is pitted, and thereafter the turret again moves to carry this pitted half fruit in its cup to the peeling station where the above described peeling operation is carried out. Simultaneously with the peeling operation the second mentioned half fruit, in its cup, is brought to the pitting station and the pitting operation is carried out on this second fruit at the same time that the peeling operation is carried out on the first half of the fruit. It will thus be seen that the series of half fruits are carried through the machine sequentially, one half being peeled at a time at the peeling station, and the other half being simultaneously pitted at the pitting station, the pitting and peeling operations being carried out simultaneously and the turret shifted sixty degrees between operations, each time.

It is thought that the invention and numerous 20 of its attendant advantages will be understood from the foregoing illustrative description and it is obvious that numerous changes may be made in the form, construction and arrangement of the several parts without departing from the 25 spirit or scope of the invention or sacrificing any of its attendant advantages, the form herein described being a preferred embodiment for the purpose of illustrating the invention.

Having thus described our invention, what we 30 claim as new and desire to secure by Letters Patent is:

We claim:

1. The herein described process which comprises holding a whole fruit having a suture plane, 35 with its suture plane vertical and with its longitudinal stem axis inclined substantially thirty degrees with respect to the horizontal and with the stem cavity end lower than the opposite end of the peach, halving the peach while so held and then swinging each half peach ninety degrees about parallel horizontal axes lying parallel to the plane of severance whereby to position each half peach with its cut face horizontal and with the projections of their longitudinal stem axes 45 intersecting at an angle of sixty degrees.

2. The herein described method which comprises holding a whole fruit having a suture plane, with its suture plane vertical and its longitudinal stem axis inclined substantially thirty degrees with respect to the horizontal plane and with the stem cavity of the whole fruit outermost and lower than the opposite end of the peach at the stem axis, peeling the stem cavity of the peach while so held, and thereafter halving the peach while so held, maintaining the same relative position of the peach halves shifting said peach halves along parallel rectilinear paths, swinging each peach half about a horizontal axis lying parallel to and in spaced relation with such last mentioned paths whereby to position each peach half so that its cut face is horizontal and uppermost and with the projections of the longitudinal stem axes of the peach halves intersecting at an angle of sixty degrees.

3. The herein described method which comprises positioning a whole fruit having a suture plane, with its suture plane disposed in a predetermined plane and with the longitudinal stem axis of the fruit inclined thirty degrees to a plane which lies at right angles to said first mentioned plane, halving the whole fruit while so positioned and maintaining the halves in such position and confronting each other, swinging each fruit half substantially ninety degrees about an axis lying in the second mentioned plane and which axis is

31

parallel to the plane of severance of said confrontingly positioned halves, to position each fruit half with its cut face disposed in said second mentioned plane and with the projections of the longitudinal stem axes of the fruit halves intersecting at an angle of sixty degrees.

4. The herein described method which comprises positioning a whole fruit having a suture plane, with its suture plane disposed in a predetermined plane and with its longitudinal stem axis of the fruit inclined thirty degrees to a second plane that lies at right angles to said first mentioned plane, halving the whole fruit and then swinging the fruit halves substantially ninety degrees about parallel spaced axes which are parallel to the plane of severance and which axes lie in the second plane whereby to position said fruit halves in spaced relation and with their cut faces in said second mentioned plane and with the projections of their longitudinal stem axes intersecting at an angle of sixty degrees.

5. The herein described method which comprises positioning a whole fruit having a suture plane, with its suture plane disposed in a predetermined plane and with the longitudinal stem axis of the fruit inclined thirty degrees to a second plane that lies at right angles to said first mentioned plane, halving the whole fruit and then swinging the fruit halves about parallel spaced axes which lie in a plane parallel to said second mentioned plane to position the cut faces of said fruit halves in planes parallel to said second mentioned plane and with the projections of said longitudinal stem axes of said fruit halves intersecting at an angle of sixty degrees.

6. The herein described method which comprises positioning a whole fruit having a suture plane with its suture plane disposed in a predetermined plane and with the longitudinal stem axis of the fruit inclined thirty degrees to a second plane that lies at right angles to said first mentioned plane, halving the whole fruit and swinging the confronting fruit halves substantially ninety degrees about parallel spaced axes lying in a common plane which is inclined relatively to the longitudinal stem axis of the confronting fruit halves, to position the cut faces of the fruit halves in spaced relation and in a common plane and with the projections of the longitudinal stem axes intersecting at an angle of sixty degrees.

7. The herein described method which comprises positioning a whole fruit having a suture plane, with its suture plane disposed in a predetermined plane and with the longitudinal stem axis of the fruit inclined thirty degrees to a second plane that lies at right angles to said first mentioned plane, halving the whole fruit, spacing the confronting cut faces of the fruit halves slightly apart but maintained in substantial parallelism and registration with each other, and thereafter swinging each half fruit about spaced apart parallel axes which are inclined to the longitudinal stem axes of the half fruits so positioned whereby simultaneously to swing the half fruits so that their cut faces lie in substantially a common plane which is parallel to said second mentioned plane and with the projections of said longitudinal stem axes of said fruit halves intersecting at an angle of sixty degrees.

8. The herein described method which comprises positioning a whole fruit having a suture plane with its suture plane disposed in a predetermined plane and with the longitudinal

32

stem axis of the fruit inclined thirty degrees to a second plane that lies at right angles to said first mentioned plane, halving the whole fruit, maintaining the relative position of the fruit halves and swinging each fruit half about parallel axes lying in a common plane disposed substantially below the position of the fruit halves when in confronting relation, and which common plane is inclined with relation to the stem axes of the fruit halves within such confronting position, whereby to position said fruit halves in spaced relation on each side of said parallel axes and substantially in the plane thereof and with the projections of said longitudinal stem axes of the half fruits intersecting at an angle of sixty degrees.

9. The herein described method which comprises positioning a whole fruit having a suture plane, with its suture plane disposed in a predetermined plane and with the longitudinal stem axis of the fruit inclined thirty degrees to a plane which lies at right angles to said first mentioned plane, halving the whole fruit while so positioned and maintaining the halves in such position and confronting each other, swinging each fruit half substantially ninety degrees about an axis lying in the second mentioned plane and which axis is parallel to the plane of severance of said confrontingly positioned halves, to position each fruit half with its cut face disposed in said second mentioned plane and with the projections of the longitudinal stem axes of the fruit halves intersecting at an angle of sixty degrees, moving said fruit halves arcuately about the point of intersection of the projections of said stem axes to positions spaced from the first mentioned position of said fruit halves, and forming arcuate lines of cut about the longitudinal stem axes of said fruit halves and through the flesh of the fruit halves whereby to remove those undesired portions of the half fruits which are positioned predetermined radial distances from said longitudinal stem axes.

10. The herein described method which comprises positioning a whole fruit having a suture plane with its suture plane disposed in a predetermined plane and with the longitudinal stem axis of the fruit inclined thirty degrees to a plane which lies at right angles to said first mentioned plane, halving the whole fruit while so positioned and maintaining the halves in such position and confronting each other, swinging each fruit half substantially ninety degrees about an axis lying in the second mentioned plane and which axis is parallel to the plane of severance of said confrontingly positioned halves, to position each fruit half with its cut face disposed in said second mentioned plane and with the projections of the longitudinal stem axes of the fruit halves intersecting at an angle of sixty degrees, arcuately shifting said half fruits from their last mentioned position to further positions with their cut faces substantially in a common plane and spaced apart, forming arcuate lines of cut with axes disposed adjacent and parallel to the longitudinal stem axis of the half fruit and beginning at the cut faces of said half fruit adjacent the pit section, whereby to remove the pit of the half fruit while said cut faces of said half fruits are substantially in said common plane.

11. The herein described method which comprises positioning a whole fruit having a suture plane, with its suture plane disposed in a predetermined plane and with the longitudinal

75

stem axis of the fruit inclined thirty degrees to a plane which lies at right angles to said first mentioned plane, halving the whole fruit while so positioned and maintaining the halves in such position and confronting each other, swinging each fruit half substantially ninety degrees about an axis lying in the second mentioned plane and which axis is parallel to the plane of severance of said confrontingly positioned halves, to position each fruit half with its cut face disposed substantially in said second mentioned plane and with the projections of the longitudinal stem axes of the fruit halves intersecting at an angle of sixty degrees, forming an arcuate cut through the flesh of one of the half fruits just beneath the skin and about an axis parallel to and substantially on the longitudinal stem axis of said half fruit while substantially in said common plane whereby to peel said half fruit.

12. The herein described method which comprises positioning a whole fruit having a suture plane, with its suture plane disposed in a predetermined plane and with its stem axis disposed substantially in said predetermined plane but inclined substantially thirty degrees to a second plane lying at right angles to and intersecting said first mentioned plane, halving the whole fruit while so positioned, and thereafter swinging each fruit half substantially ninety degrees so that said fruit halves lie spaced apart with their cut faces exposed and in a substantially common plane located at right angles to said predetermined plane, with the projections of their longitudinal stem axes angularly disposed and forming an angle of substantially sixty degrees.

13. The herein described method which comprises positioning a whole fruit having a suture plane with its suture plane disposed in a predetermined plane and with its stem axis disposed substantially in said predetermined plane but inclined substantially thirty degrees to a second plane lying at right angles to and intersecting said first mentioned plane, halving the whole fruit while so positioned, and thereafter swinging each fruit half substantially ninety degrees so that said fruit halves lie spaced apart with their cut faces exposed and in a substantially common plane normal to said first mentioned predetermined plane and with the projections of their longitudinal stem axes forming an angle of substantially sixty degrees, forming an arcuate cut through the flesh of one of the half fruits, said arcuate cut being formed about an axis substantially parallel to the longitudinal stem axis of said half fruit while substantially in said common plane.

14. The herein described method which comprises positioning a whole fruit having a suture plane with its suture plane disposed in a predetermined plane and with its stem axis disposed substantially in said predetermined plane but inclined substantially thirty degrees to a second plane lying at right angles to and intersecting said first mentioned plane, halving the whole fruit while so positioned, and thereafter swinging each fruit half substantially ninety degrees so that said fruit halves lie spaced apart with their cut faces exposed and in a substantially common plane normal to said first mentioned predetermined plane and with the projections of their longitudinal stem axes forming an angle of substantially sixty degrees, simultaneously forming arcuate cuts through the flesh of the two half fruits while said half fruits are so positioned, said arcuate cuts being formed about axes sub-

stantially parallel to the longitudinal stem axes of said half fruits.

15. The herein described method which comprises positioning a whole fruit having a suture plane, with its suture plane disposed in a predetermined plane and with its stem axis disposed substantially in said predetermined plane but inclined substantially thirty degrees to a second plane lying at right angles to and intersecting said first mentioned plane, halving the whole fruit while so positioned, and thereafter swinging each fruit half substantially ninety degrees so that said fruit halves lie spaced apart with their cut faces exposed and in a substantially common plane normal to said first mentioned predetermined plane and with the projections of their longitudinal stem axes forming an angle of substantially sixty degrees, forming arcuate cuts through each of the half fruits so positioned,

20 one of the arcuate cuts so formed being about the longitudinal stem axis of one of the fruit halves, and the other of the arcuate cuts being formed about an axis parallel to and relatively close to the longitudinal stem axis of said other half fruit.

25 16. The herein described method which comprises positioning a whole fruit having a suture plane with its suture plane disposed in a predetermined plane and with its stem axis disposed substantially in said predetermined plane but inclined substantially thirty degrees to a second plane lying at right angles to and intersecting said first mentioned plane, halving the whole fruit while so positioned, and thereafter swinging each fruit half substantially ninety degrees so that said fruit halves lie spaced apart with their cut faces exposed and in a substantially common plane normal to said first mentioned predetermined plane and with the projections of their longitudinal stem axes forming an angle of substantially sixty degrees, simultaneously forming arcuate cuts through the flesh of both of the half fruits, said arcuate cuts being formed with varying radii and about respective axes substantially coinciding with the stem axes of the two half fruits so positioned, whereby to peel one of the half fruits while pitting the other half fruit.

30 17. The herein described method which comprises positioning a whole fruit having a suture plane, with its suture plane disposed in a predetermined plane and with its stem axis disposed substantially in said predetermined plane but inclined substantially thirty degrees to a second plane lying at right angles to and intersecting said first mentioned plane, halving the whole fruit while so positioned, and thereafter swinging each fruit half substantially ninety degrees so that said fruit halves lie spaced apart with their cut faces exposed and in a substantially common plane normal to said first mentioned predetermined plane and with the projections of their longitudinal stem axes forming an angle of substantially sixty degrees, forming arcuate cuts through the flesh of the half fruit about axes lying parallel to the longitudinal stem axis of the half fruit, whereby to simultaneously pit and peel the two half fruits while so positioned.

35 18. The herein described method which comprises substantially identically positioning a succession of whole peaches with their successive suture planes parallel to and adjacent a predetermined vertical plane and each with its stem axis inclined substantially thirty degrees to the horizontal, successively halving each whole peach while so positioned, thereafter swinging the first

and second fruit halves of the first peach so that the first and second halves of said peach lie substantially in a common plane and with the projections of their longitudinal stem axes intersecting at an angle of substantially sixty degrees, forming an arcuate cut through the flesh of the first half peach only, such cut being formed about an axis coinciding with the longitudinal stem axis of such half fruit whereby to pit the half fruit, thereafter moving the two half fruits, while maintained in position in such common plane, substantially sixty degrees, the next whole peach meanwhile having been positioned in substantially the identical first mentioned position of the first peach, halving the second mentioned peach while so positioned and, simultaneously with the last mentioned movement of the first peach, swinging the cut halves of the second peach into substantially the same common plane as the cut halves of the first mentioned peach and with the projections of the longitudinal stem axes of the halves of the second mentioned peach spaced apart sixty degrees and with the nearest half of the second mentioned peach disposed so that the projection of its longitudinal stem axis is angularly spaced sixty degrees from the projection of the longitudinal stem axis of the nearest half peach of the first mentioned peach, and thereafter simultaneously forming arcuate cuts through the flesh of the first half of the first mentioned peach, and through the flesh of the second half of the first mentioned peach, said first cut being formed as a peeling cut just beneath the peel and about an axis parallel with the longitudinal stem axis of the first half of the first mentioned peach, and the second cut being formed about an axis coinciding with the stem axis of the second half of the first mentioned peach and relatively close to the pit section of the second mentioned peach, whereby simultaneously to peel the first half of the first mentioned peach and to pit the second half of the first mentioned peach.

19. The herein described method which comprises positioning a succession of whole peaches, each with its suture plane disposed parallel to and adjacent a predetermined plane and each with its stem axis lying substantially in said predetermined plane but inclined substantially thirty degrees to a plane intersecting and lying perpendicularly to said first mentioned plane, and each with its longitudinal stem axis inclined to a plane which lies at right angles to the first mentioned plane, halving each whole fruit while so positioned, and thereafter successively and simultaneously swinging the fruit halves of each peach substantially ninety degrees about an axis lying in the third mentioned plane and which axis is parallel to the plane of severance of said confrontingly positioned halves whereby to position each fruit half with its cut face disposed substantially in the third mentioned plane and with the projections of their longitudinal stem axes intersecting at an angle of sixty degrees,

thereafter moving the so positioned fruit halves angularly in said common plane sixty degrees while positioning the fruit halves of the next succeeding peach in exactly the positions of the fruit halves formerly occupied by the first mentioned peach, and simultaneously forming arcuate cuts through the flesh of two adjacent fruit halves while lying in said common plane and spaced sixty degrees apart, one of said cuts being arcuately formed about an axis coinciding with the stem axis of one of said fruits and substantially close to the border line of the pit, whereby to pit said half fruit, and the other arcuate cut being formed about an axis lying parallel and adjacent the stem axis of the other half fruit and just underlying the skin of said half fruit, whereby to peel the same.

20. The method of feeding peaches which comprises holding the peach with its suture plane vertical and with its stem axis inclined about thirty degrees to the horizontal while bisecting the whole fruit through a plane parallel to and adjacent to its suture plane, maintaining such position of the fruit halves while feeding the fruit halves along parallel paths with the planes of the cut faces of the fruit halves perpendicular to the horizontal, and with the stem axes of the fruit halves so inclined to the horizontal, and simultaneously swinging both fruit halves about parallel axes which are parallel to the horizontal and into spaced apart positions such that their cut faces lie in substantially a common plane and with the projections of their stem axes intersecting at an angle of about sixty degrees.

21. The herein described method which comprises positioning a whole fruit having a suture plane, with its suture plane disposed in a predetermined plane and with its stem axis substantially lying in said predetermined plane but inclined substantially thirty degrees to a second plane normal to and intersecting said first mentioned plane, halving the whole fruit while so positioned in a plane substantially parallel to and substantially coincident with said suture plane, and thereafter swinging the fruit halves apart so that said fruit halves lie spaced apart with their cut faces exposed and in a substantially common plane with the projections of their longitudinal stem axes forming an angle of substantially sixty degrees.
